Patented Jan. 12, 1960

187,050

BOTTLE CARRIER OR THE LIKE

Theodore F. Erickson, Des Moines, Iowa

Application November 24, 1958, Serial No. 53,481

Term of patent 14 years

(Cl. D58—5)

Fig. 1

Fig. 2

Fig. 3

Fig. 1 is a bottom perspective view of a bottle carrier or the like, showing my new design;

Fig. 2 is a bottom plan view thereof; and

Fig. 3 is a side elevational view thereof.

The dominant features of my design reside in the portions shown in full lines.

I claim:

The ornamental design for a bottle carrier or the like, as shown and described.
